UNITED STATES PATENT OFFICE.

ALFRED ORTON, OF CHEYENNE, WYOMING.

JIG ATTACHMENT FOR PLANERS.

1,115,966.

Specification of Letters Patent.

Patented Nov. 3, 1914.

Application filed January 17, 1914. Serial No. 812,774.

To all whom it may concern:

Be it known that I, ALFRED ORTON, a citizen of the United States, residing at Cheyenne, in the county of Laramie and State of Wyoming, have invented a new and useful Jig Attachment for Planers, of which the following is a specification.

The present invention appertains generally to metal planers, and relates more particularly to a jig or templet attachment therefor.

It is the object of the present invention to provide a novel and improved jig for holding the pedestal shoes and wedges of locomotive driving boxes, whereby their faces may be conveniently and efficiently planed.

Another object of the present invention is to provide a device of the nature indicated which will be attachable to the bed or table of various planers, and which will be provided with means for properly setting it with respect to the planer bed or table, so that the pedestal shoe or wedge may be properly planed.

A further object of the present invention is to provide a device of the character specified which will conveniently accommodate various styles and sizes of pedestal shoes and wedges, and which shall be adjustable 30 to accommodate the various wedges and shoes.

A still further object of the present invention is to provide a novel apron or guard carried by the body of the jig, and which is adapted to coöperate with the planer bed or table, to prevent chips or other foreign objects from passing between the jig body and the planer bed or table.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The present invention has been illustrated in its preferred embodiment in the accompanying drawings, wherein:

Figure 1 is a plan view of the improved

jig. Fig. 2 is a side elevation thereof. Fig. 3 is a cross section of the device, taken on the line 3—3 of Fig. 1. Fig. 4 is an enlarged sectional detail of one of the contrivances for adjusting the jig body, the section being taken on the line 4—4 of Fig. 1. Fig. 5 is a fragmental bottom view of one corner of the jig body, illustrating the device depicted in Fig. 4. Fig. 6 is a sectional detail illustrating the adjustable apron.

In carrying out the present invention, reference being had in detail to the drawings, there is provided a body 1, preferably in the form of a suitable casting, and approximately rectangular in contour. This body 1 is of the proper size or proportions, so as to accommodate the pedestal shoes and wedges as will hereinafter appear. The body 1 is provided with a depending longitudinal tongue 2 along its longitudinal median plane, which tongue is adapted to engage the groove or a planer bed or table, to hold the body in position upon a planer bed or table, as will be apparent. The ends of the body 1 have slots 1^a for the passage of bolts or other fastening devices to engage the planer bed or table.

The top or upper side of the body 1 is provided with an upstanding longitudinal jaw 3 adjoining the longitudinal median line of the body. To one side of the jaw 3, the upper face of the body is provided with a depression or cut away portion 4 extending from the jaw 3 to the respective edge of the body, the depression 4 and jaw 3 being preferably co-extensive, and terminating short of the ends of the body.

Disposed in the depression or cut away portion 4, is a plate or slide 5, which is preferably flush with the top of the body, and which has an upstanding jaw 6 along its inner edge coöperating with the jaw 3. The plate or slide 5 and its jaw 6 are co-extensive with the jaw 3, the jaw 3 being preferably relatively wide, while the jaw 6 is relatively thin or narrow.

The plate or slide 5 and the body 1 are provided with the upstanding ribs or flanges 7 and 8, respectively, parallel with the jaws and disposed at the remote sides of the jaws and adjacent the respective side edges of the body. The flanges or ribs 8 each carry a series of jam or clamping bolts 9 which are directed toward the respective jaws.

The upper portions of the jaws 3 and 6 are cut-away intermediate their ends, to provide the inclined depressions 10 to accommodate the pedestal wedges, as hereinafter described, and adjoining the shoulders formed by the depressions 10, the jaws are provided with the upper stops 11. The jaw 3 is provided with vertical bores or holes 12 adjoining the respective stop 11, and the lower ends of these bores 12 are directed out through the sides of the jaw 3, as clearly seen in Fig. 3.

The plate or slide 5 is adapted to be adjusted laterally within the depression 4, to move the jaw 6 to and from the jaw 3, and to this end, the body 1 is formed with T-slots 13 at the bottom of the depression 4 and extending inwardly from the respective edge of the body, as clearly seen in Fig. 3. Draft or clamping bolts 14 are carried by the plate or slide 5, and have nuts 15 threaded on their upper ends and bearing against the top of the slide 5, while the heads 16 of the bolts engage under the shoulders of the slots or grooves 13. When the bolts 14 are loosened, it will be evident that the slide 5 may be adjusted as desired, and that when the bolts are tightened, through the medium of the nuts 15, the plate or slide 5 will be securely clamped within the depression 4 of the body. The slide 5 may be removed or detached from the body by disengaging the headed ends of the bolts 14 from the body, as will be obvious.

A guide plate 17 extends around the sides and ends of the body 1, the upper edge of the plate 17 being secured in any suitable manner to the body, in order that the plate 17 will depend over the respective sides and ends of the body. The plate 17 is cut away to accommodate the slide 5, and is also provided with the T-slots or openings 18 registering with the similar slots or grooves 13 of the body, in order to permit the bolts 14 to be engaged with and disengaged from the body.

A sheet metal apron 19 is snugly disposed between the plate 17 and the body 1, so as to slide or reciprocate vertically, the upper edge of the apron 19 terminating short of the upper edge of the guide plate 17. The apron 19 is also provided with upwardly opening slots or recesses 20 registering with the slots 18 and 13, to permit of the introduction and withdrawal of the bolts 14, as above intimated. The apron 19 is spring pressed downwardly so as to seat upon the planer bed or table. To this end, coiled wire springs 21 are seated within sockets or depressions 22 in the sides and ends of the body 1, and engage the upper portion of the apron 19 to yieldingly depress the apron. The upper edge of the apron 19 is preferably provided with instruck ears 23 work-

ing within the depressions 22, and against which the springs seat, to force the apron downwardly, although other means may be provided for spring pressing the apron.

It is preferable to provide closure strips 24 adapted to be inserted between the guide plate 17 and the apron 19, to close the slots or openings 18 and 20, for preventing chips or other extraneous matter from entering the slots or grooves 13 of the body. These members 24 may be readily inserted and withdrawn, as necessary.

The four corners of the body 1 are each provided with means for setting or truing the body 1 upon the planer bed or table, and inasmuch as the said means are duplicates of one another, only one need be described in detail.

Each corner of the body 1 is provided with an upright bore or opening 25, the upper end of which is contracted or reduced in diameter, as at 26, and that portion of the bore next inside or adjoining the reduced portion 26, is hexagonal or non-circular in cross section, as at 27. Diametrically opposed longitudinal channels 28 are provided adjoining the lower end of the bore or opening 25, the channels 28 extending from the bottom of the body to a point short of the contracted or reduced portion 26. A bushing or collar 29 is inserted upwardly through the bore 25 within the contracted or reduced portion 26, and is provided at its lower end with an enlarged portion or head 30 of hexagonal contour fitting snugly within the portion 27 of the bore 25 and seating against a shoulder 31 provided by the portion 27 and contracted portion 26. The upper end of the collar 29 projects above the top of the body, and a binding nut 32 is threaded onto the upper end of the bushing or collar 29 and bears against the top of the body to clamp the bushing or collar tightly in position. A foot 33 of noncircular cross section is slidable within the lower end of bore 25, and has the diametrically opposite lugs 34 at its upper end engaging within the respective channels 28, plug screws 35 being threaded into the outer ends of the channels 28 to limit the outward movement of the lugs 34 to thereby retain the foot 33 in engagement with the body. The lugs 34 are adapted to slide within the channels 28 and to correspondingly permit the foot to slide, whereby the foot may be projected and retracted relative to the bottom of the body. A jam bolt 36 is threaded through the collar or bushing 29 and has its tip rounded and engaging a rounded socket or depression formed in the top of the foot 33, whereby the foot 33 may be depressed through the medium of the jam bolt 36. A coiled wire spring 37 is interposed between the collar 29 and the foot 33, around

100

125

the jam bolt 36, to yieldingly depress the foot 33.

As above intimated, the present jig or templet is designed for holding pedestal 5 shoes or wedges of locomotive driving boxes, such shoes and wedges being of channel-shaped cross section.

In practice, the body 1 is bolted or fastened on the planer bed or table, with the 10 tongue 2 engaged into a groove of the planer bed or table, whereby the body may be held above the same. When the body is thus applied to the planer bed or table, it will be evident that the apron 19 will be depressed 15 against the planer bed or table to close the gap between the sides and ends of the body 1 and the planer bed, in order to prevent chips or other foreign matter from working underneath the body 1. The pedestal shoe 20 or wedge to be planed is then set astride the jaws 3 and 6 with its flanges disposed over the remote sides of the jaws within the ribs or flanges 7 and 8. The slide 5 is then adjusted outwardly, in order to open the jaws 25 between the flanges of the pedestal shoe or wedge, so as to internally grip the pedestal shoe or wedge, and after the slide 5 has been properly adjusted, the same is clamped in position by the bolts 14. The jam bolts 9 30 are then threaded inwardly to clamp the flanges of the pedestal shoe or wedge against the jaws, in which event the pedestal shoe or wedge will be rigidly held or clamped upon the body, with its face exposed.

In planing the faces of pedestal shoes or wedges, considerable care is necessary in properly adapting the shoes or wedges to the pedestal or frame. This may be accomplished by properly setting the body 1 in order that the face of the pedestal shoe or wedge may be properly planed when the planer table or bed is moved under the milling cutter or the like. The body 1 may be 45 conveniently set by properly adjusting the jam bolts 36 at the various corners, it being noted that the spring 37 will ordinarily press the feet 33 against the planer bed or table. By threading the bolts 36 downwardly, the body 1 may be tilted slightly in various directions so as to properly position the pedestal shoe or wedge.

The depression 10 of the jaws are designed to accommodate the pedestal wedges, as will be evident to those versed in the art, and the stops 11 are adapted to limit the movement of the pedestal shoes and wedges toward the respective end of the jaws. The bores or channels 12 are adapted to conduct chips or 55 other foreign material downwardly away from the stop 11 of the jaw 3.

In view of the foregoing description, taken in connection with the drawings, the advantages and capabilities of the present inven-

tion will be manifest to the skilled mechanic, 65 without a lengthy description it being observed that the objects aimed at have been carried out satisfactorily.

Having thus described the invention, what is claimed as new is:—

1. A device of the character described including a body attachable to a planer bed, having a longitudinal upstanding jaw, an adjustable slide carried by the body and having an upstanding jaw adjacent the 75 aforesaid jaw, and clamping means carried by the slide and body at the remote sides of the jaws to clamp an object astride the jaws.

2. In a device of the character described, a body attachable to a planer bed and having a longitudinal upstanding jaw, a slide carried by one side portion of the body and having an upstanding jaw adjacent the aforesaid jaw, means for clamping the slide at various adjustments, the slide and body 80 having upstanding ribs parallel with and at the remote sides of the jaws, and jam bolts carried by the ribs and projecting toward the jaws to clamp an object astride the jaws.

3. In a device of the character described, 90 a body attachable to a planer bed and having a longitudinal upstanding jaw adjoining its longitudinal median line, the body having an upper depression at one side of the jaw, a slide fitting in the depression and 95 having an upstanding jaw complementing the aforesaid jaw, the body having T-slots below the slide, clamping bolts carried by the slide and engaging said slots, and clamping devices carried by the slide and body, 100 and coöperating with the respective jaws.

4. In a device of the character described, a body, the bottom of which is provided with means for engaging a planer bed, and the top of which is provided with means for 105 holding an article to be planed, and a spring pressed apron carried by the body adapted to seat on the planer bed to close the gap between the body and the planer bed.

5. In a device of the character described, 110 a body, the bottom of which is provided with means for engaging a planer bed, and the top of which is provided with means for holding an article to be planed, a guide plate secured around the sides and ends of the 115 body, and a spring pressed apron disposed between the guide plate and the body to seat against the planer bed.

6. In a device of the character described, a body, the bottom of which is provided 120 with means for engaging a planer bed, a slide adjustably mounted on one side portion of the body, the slide and body having coöperating means for holding a body to be planed, a guide plate extending around the 125 sides and ends of the body, the upper edge portion of the guide plate being attached to the body, a sheet metal apron disposed

- snugly between the guide plate and the body, and springs disposed between the apron and the body for yieldingly depressing the apron.
7. In a device of the character described, a rectangular body, the bottom of which is provided with means for engaging a planer bed, a slide mounted on one side portion of the body, the body having slots below the slide and extending to the respective side of the body, draft bolts carried by the slide and engaging the slots, the slide and body having coöperating means for holding an article to be planed, a guide plate around the sides and ends of the body, the upper edge portion of the guide plate being secured to the body, a sheet metal apron disposed snugly between the guide plate and body, means for yieldingly depressing the apron, the guide plate and apron having slots registering with the slots of the body, and closure members insertible between the guide plate and apron to close the said slots.
8. In a device of the character described, a body having a central tongue to engage a planer bed, and means on its upper face for holding an article to be planed, yieldable feet carried by the corners of the body, and jam bolts carried by the body above and coöperating with the said feet.
9. In a device of the character described, a body, the bottom of which is provided with a central tongue for engaging a planer bed, and the top of which is provided with means for holding an article to be planed, the corners of the body having vertical openings and channels extending to the lower ends of the openings, feet slidably
- mounted in the lower ends of the openings having lugs engaging the channels, members engaging the lower ends of the channels to retain the lugs within the channels, and jam bolts carried by the body above and coöperating with the feet.
10. In a device of the character described, a body, the bottom of which is provided with a central tongue for engaging a planer bed, and the top of which is provided with means for holding an article to be planed, the corners of the body having vertical openings therethrough, the upper ends of the openings being contracted and those portions of the openings adjoining the contracted portions being non-circular, the body having longitudinal channels extending to the lower ends of the openings, collars engaging in the contracted portions of the openings and having lower non-circular heads fitting snugly within the said non-circular portions of the openings, nuts threaded on the upper ends of the collars and seating on the body, feet disposed slidably within the lower ends of the openings and having upper lugs engaging the channels, members engaged within the lower ends of the channels to retain the lugs therein, jam bolts threaded through the collars to engage the feet, and coiled springs disposed between the feet and collars.
- In testimony that I claim the foregoing as my own, I have hereto affixed my signature in the presence of two witnesses.
- ALFRED ORTON.
